Primary Examiner — Shawn T Gingrich*Assistant Examiner* — Amanda Christensen(74) *Attorney, Agent, or Firm* — Daniel M. Cohn;
Howard M. Cohn(57) **CLAIM**

The ornamental design for a foldable wireless charger as shown and described.

DESCRIPTION

FIG. 1 is a perspective view of a foldable wireless charger showing my new design;

FIG. 2 is a rear perspective view thereof;

FIG. 3 is front view thereof;

FIG. 4 is a rear view thereof;

FIG. 5 is a left view thereof;

FIG. 6 is a right view thereof;

FIG. 7 is a top plan view thereof;

FIG. 8 is bottom plan view thereof; and,

FIG. 9 is another perspective view showing the design in a closed position.

The broken lines depict portions of the foldable wireless charger and form no part of the claimed design.

1 Claim, 9 Drawing Sheets(56)
